UNITED STATES PATENT OFFICE.

JOHN T. ENGLISH, OF NEWARK, NEW JERSEY.

SIGNAL-HORN.

1,184,171.

Specification of Letters Patent. Patented May 23, 1916.

Application filed June 2, 1915. Serial No. 31,654.

To all whom it may concern:

Be it known that I, JOHN T. ENGLISH, a citizen of the United States, residing at Newark, in the county of Essex and State of New Jersey, have invented certain new and useful Improvements in Signal-Horns; and I do hereby declare the following to be a full, clear, and exact description of the invention, such as will enable others skilled in the art 10 to which it appertains to make and use the same, reference being had to the accompanying drawings, and to characters of reference marked thereon, which form a part of this specification.

10 The present invention relates, generally, to improvements in signal or alarm-horns; and the invention relates, more particularly, to a novel construction of signal or alarm-horn, in which the sound is produced by mechanically agitating or vibrating a diaphragm or sounding-plate to generate sound-waves of high penetrating quality.

25 The principal object of the present invention is to provide a novel construction of diaphragm or sounding-plate agitator-means, together with a very simple and effective means of applying a primary motive impulse or force thereto to set the same in operation.

30 A further object of the invention is to provide a novel construction of diaphragm or sounding-plate agitator of a rotary form, which is capable of continued rotation or movement through acquired momentum, after receiving the initial application of motive force; and a still further object of the invention is to provide, in connection with said agitator, a novel means of applying or transmitting an initial motive power or force thereto, the same being so constructed as to automatically disconnect itself from the agitator after imparting thereto the necessary initial motive impulse, so that said agitator may continue its operative movement, independently of said power-applying or transmitting means, by virtue of its acquired momentum.

35 Other objects of the present invention, not at this time more particularly enumerated, will be clearly understood from the following detailed description of the same.

With the various objects of the present invention in view, the said invention consists, generally, in the novel construction of signal or alarm-horn hereinafter set forth;

and, the invention consists, furthermore, in the novel arrangements and combinations of the various devices and parts, as well as in the details of the construction of the same, all of which will be more fully described in 60 the following specification, and then finally embodied in the claims which are appended to and which form an essential part of the said specification.

The invention is clearly illustrated in the 65 accompanying drawings, in which:—

Figure 1 is a side elevation of the novel construction of signal or alarm-horn, made according to and embodying the principles of my present invention. Fig. 2 is a longitudinal section of the same, showing however the agitator and connected parts in elevation. Fig. 3 is a detail longitudinal section of said novel signal or alarm-horn, drawn on an enlarged scale, and showing 70 both the agitator and power-transmitting means in section and in normal initial position; Fig. 4 is a view similar to Fig. 3, but showing the operation of the power transmitting means relative to said agitator. Fig. 80 3^a is a fragmentary detail longitudinal section of a portion of the operating mechanism of said agitator, drawn on a still larger scale. Fig. 5 is a detail transverse horizontal section, taken on line 5—5 in said Fig. 3, 85 the same being drawn on an enlarged scale. Fig. 6 is a detail elevation of the upper end of said agitator, showing the automatic coupling device or clutch of the power-transmitting means in operative relation or connection therewith, said view being also drawn on an enlarged scale. 90

Similar characters of reference are employed in all of the hereinabove described views, to indicate corresponding parts. 95

Referring now to the several figures of the drawings, the reference character 1 indicates the complete signal or alarm-horn made according to and embodying the principles of my present invention, the same comprising 100 a shell-like body or casing 2 which is open at one end. Said shell-like body or casing 2 is provided at the marginal edges of its open end with an outwardly extending annular flange 3, the inner side of which forms a seat. Said annular flange 3 is provided with a rim or flange 4 extending forwardly at right angles thereto. Arranged upon said seat formed by said annular flange 3, so as 110 to extend across the opening of said shell-

like body or casing 2, is a diaphragm or sounding plate 5. The reference character 6 indicates a horn-body, of any usual or desirable shape or configuration, the same having at its inner end an outwardly extending annular base-flange 7. The said base-flange 7 is of such a diameter as to permit the same to fit snugly within the rim or flange 4 and against 10 the diaphragm or sounding-plate 5, so that the marginal edges of the latter are held firmly clamped between said base-flange 7 and said annular flange 3 of the body or casing 2. Suitable bolts 8 are passed transversely through said respective flanges 3 and 7 and the marginal edges of said diaphragm or sounding-plate arranged therebetween, and firmly fixed against removal by nuts 9, thus securely binding together said parts in 15 20 the above described relation. Suitably secured in a centrally disposed position upon said diaphragm or sounding-plate 5 is an impingement receiving head or button 10, which is arranged to project into said body or casing 2. Secured in the lower side of said body or casing 2 is a bushing 11 which is provided with an internally screw-threaded opening in which is adjustably arranged a journal stud or pin 12, provided 25 30 at its upper end with a cone-shaped bearing-point or head 13. Secured in the upper side of said body or casing 2 is a bushing 14, the lower portion of which projects interiorly into said body or casing 2, while the upper portion of the same projects exteriorly from 35 said body or casing 2. The lower portion of said bushing 14 is chambered, as at 15, and extending upwardly from said chambered portion 15 is a tubular bearing or guide- 40 opening 16, which is of reduced diameter as compared with the diameter of said chamber 15. Said bushing 14, as thus formed, is aligned vertically above the bushing 11 in the lower side of said body or casing 2.

45 The reference character 17 indicates a rotary agitator-element provided with the oppositely and vertically extended hub-portions 18. The end of said lower hub-portion is provided with a cone-shaped seat 19 adapted to engage and be rotatably supported upon said cone-shaped bearing-point or head 13 of said journal stud or pin 12. The end of said upper hub-portion is reduced in diameter to provide a journal-portion 20 adapted to be rotatably journaled in the end of said chamber 15 of said bushing 14. Extending downward and vertically through the hub-portions 18 of said agitator-element 17 is a tubular receiving chamber or slideway 21. As thus constructed and disposed, said agitator-element is arranged to rotate in a horizontal plane, and its periphery is provided with a plurality of agitating teeth or serrations 22 which normally contact or impinge upon said im-

pingement receiving head or button 10 of said diaphragm or sounding-plate 5. Connected with said agitator-element is a disk-like extension 23 which adds weight to the same and performs the function of a balance or momentum-wheel.

The reference character 24 indicates a power transmitting screw-shank which is provided with double threads 25 thus providing double thread-channels 26. Said screw-shank 24 is inserted in the guide-opening 16 of said bushing 14 and passed downwardly therethrough so that its lower end extends into the receiving-chamber or slideway 21 of said agitator-element, the diameter of the latter being such that a free sliding up and down movement of said screw-shank in the same is permitted without interfering with the free rotation of said agitator-element. The outer end of said screw-shank is provided with a suitable thrust-head 27, which can be engaged by the hand of the operator to impart to said screw-shank a downward operative thrust or movement. Extending upwardly from the lower end of said screw-shank 24 is a tubular receiving chamber or socket 28. Inserted in said chamber or socket 28 is a coiled compression spring 29, the lower end of which extends downwardly through said slideway 21 of said agitator element, so as to be seated against the upper end of said journal stud or pin 12, the lower end of said slideway 21 terminating in a hole or opening 30 of reduced diameter as to conform the same to the end of said spring and maintain the latter properly seated on said journal stud or pin, against which the spring thrusts when under compression. Inserted through the lower end of said spring 29 is a keeper-rod 31, the upper end of which just enters said socket 28 of said screw-shank 24 when the latter is in normal upwardly moved or initial position. Said keeper-rod 31 tends to prevent the spring 29 from buckling when placed under compression by the downwardly moving screw-shank 24, and thus prevents the same from obstructing the operative downward movement of said screw-shank in said slideway 21.

The reference character 32 indicates a coupling or clutch-element in the form of a ring-like member which surrounds the screw-shank 24, and which is provided with inwardly projecting lugs or projections 33 which enter respectively the thread-channels 26 so as to be engaged operatively by the double screw threads 25 of said screw-shank 24. Said coupling or clutch-element 32 is arranged in said chamber 15 of the bushing 14, above the journal portion 20 of said agitator-element, and is capable of a vertical play or movement within said chamber. The lower end or side of said coupling or clutch-element 32 is provided with a series

of chamfered ratchet-like teeth 34, which normally engage a series of oppositely presented similar chamfered ratchet-like teeth 35 with which the free end of said journal-portion 20 of said agitator-element 17 is provided. A cylindrical stop-nut 36, which is adapted to be secured or screwed upon the lower end of said screw-shank 24, after said coupling or clutch-element 32 has been operatively assembled therewith, serves to prevent the removal of said screw-shank 24 from operative relation to said coupling or clutch-element, and also to limit the normal upwardly moved or initial position of said screw-shank 24 relative to the mechanism with which it is connected, and which it is designed to operate.

When the several parts of my novel construction of signal or alarm-horn are constructed and assembled as above described, the same may be operated in the following described manner. The screw-shank 24 is hit with the hand and thrust or pressed downward. In traveling downward, its threads are carried into operative engagement with the lugs or projections 33 of said coupling or clutch-element 32, imparting to the latter a rotary movement, at the same time the downward movement of the screw-shank 24 forces said coupling or clutch element 32 downward, so that its clutch-teeth 34 are carried into mesh and operative engagement with the clutch-teeth 35 of said journal-portion 20 of the upper hub 18 of said agitator-element 17, thus imparting to the latter the rotary movement imparted to the coupling or clutch-element by said screw-shank, as above mentioned. This operation results in transmitting to said agitator-element a quick rotary or spinning movement, whereby its agitating teeth or serrations 22 are rapidly and successively impinged upon the impingement receiving button or head 10 of said diaphragm or sounding-plate 5, thereby causing a rapid vibration or agitation of the latter which results in a sound-production providing an alarm or signal, the sounds thus produced being amplified and mellowed, *i. e.* rendered less metallic and more musical, by the horn-body 6 into which they are discharged or directed. In thus transmitting to said agitator-element 17 a rapid spinning movement, the same acquires a certain amount of momentum which will tend to maintain its continued rotation with operative effect upon said diaphragm or sounding-plate 5, even after the direct application of motive force, transmitted in the manner above described, has ceased. From such novel operation, a distinctive or characteristic siren-like sound may be produced, which is not only sudden and penetrating at its initiation, but is sustained with decreasing pitch as the agitator-element slows up by reason

of its loss of momentum, the resulting sound being a loud and piercing tone at the beginning which gradually trails off or diminishes both in intensity and pitch. It will thus be apparent, that the horn is very well adapted for signal and alarm purposes, such as for use on automobiles, power-boats and similar places. The operator secures a long time-period of sustained alarm sound with a minimum initial manual operation. After the downward thrust or movement of said screw-shank 24 has been manually accomplished, the hand is removed therefrom, and the tension stored by the compression of the spring 29 forces upward said screw-shank 24, returning the same to normal initial position. As said screw-shank moves upward it lifts said coupling or clutch-element 32 to the upper end of said chamber 15, and maintains said clutch-teeth 34 thereof out of engagement with the clutch-teeth 35 of said journal portion 20 of the agitator element, thus allowing the latter to continue its spinning movement by momentum, as already above mentioned. Even though said screw-shank 24 should be held down by the hand the spinning movement of said agitator element would not be obstructed by said coupling or clutch-element 32, since as soon as the downward pressure of the screw-shank ceases, the clutch-element 32 is free to ride upward, as the chamfered sides of the respective clutch-teeth will permit the same to separate, and the clutch-teeth 35 of the journal portion 20 of the agitator-element to ride or move ahead of the clutch-teeth 34, so that the clutch-element will lift free, and thus will not interfere with the continued rotation of the agitator-element under the force of its acquired momentum.

From the above description it will be clearly understood, that my present invention provides a very cheap and yet efficient construction of signal or alarm horn, capable of producing a comparatively sustained sound-note or alarm, under a minimum of normal operation, and at the same time the mechanism is of exceedingly simple character with no parts easily disarranged or rendered inoperative, and a mechanism very easy and simply operated to produce the sound desired.

I am fully aware that changes may be made in the various arrangements and combinations of the several devices and parts, as well as in the details of the construction of the same, without departing from the scope of my present invention, as described in the foregoing specification and as defined in the claims appended thereto. Hence, I do not limit my invention to the exact arrangements and combinations of the various devices, and parts as set forth in the said specification, nor do I confine myself to the

exact details of the construction of said parts as illustrated in the accompanying drawings.

I claim:

1. An alarm horn comprising a casing, a diaphragm secured over the open end of said casing, an impingement-receiving button on said diaphragm, a rotary agitator element mounted in said casing having teeth adapted to impinge when rotated upon said impingement-receiving button, said agitator element having oppositely extending hubs, an adjustable journal-stud affixed to said casing upon which the lower hub is pivoted, a bushing fixed to said casing having a chamber in its inner end and a guide-opening extending therefrom outwardly to its outer end, the upper hub having a bearing-portion journaled in said chamber, said agitator and its hubs having a longitudinal tubular slideway formed therein, a self-releasing clutch arranged in said chamber of said bushing above the journal-portion of said agitator, means in said journal-portion adapted to receive the operative engagement of said clutch, a double-threaded screw-shank arranged to pass through said guide-opening of said bushing and enter the slideway of said agitator, and means on said clutch adapted to be operatively engaged by the threads of said screw-shank whereby a rotary movement may be imparted to said clutch by an inward movement of said screw-shank, and spring-means for returning said screw-shank to normal position after operation.
2. An alarm horn comprising a casing, a diaphragm secured over the open end of said casing, an impingement-receiving button on said diaphragm, a rotary agitator-element mounted in said casing having teeth adapted to impinge when rotated upon said impingement-receiving button, said agitator-element having oppositely extending hubs, an adjustable journal-stud affixed to said casing upon which the lower hub is pivoted, a bushing fixed to said casing having a chamber in its inner end and a guide-opening extending therefrom outwardly to its outer end, the upper hub having a bearing-portion journaled in said chamber, said agitator and its hubs having a longitudinal tubular slideway formed therein, a self-releasing clutch arranged in said chamber of said bushing above the journal-portion of said agitator, a plurality of chamfered clutch-teeth formed on the under side of said clutch, a corresponding plurality of oppositely chamfered clutch-teeth formed on the bearing-portion of said upper hub adapted to be operatively engaged by the clutch-teeth of said clutch, a double-threaded screw-shank arranged to pass through said guide-opening of said bushing and enter the slideway of said agitator, inwardly projected lugs on said clutch adapted to be engaged by the threads of said screw-shank whereby a rotary movement is imparted to said clutch by an inward movement of said screw-shank, said screw-shank having a tubular receiving socket in its lower end, a compression spring arranged in said socket and extending down upon the end of said journal-stud, and a keeper rod extending through the lower portion of said spring.
3. An alarm horn, comprising a casing, a diaphragm secured over the open end of said casing, an impingement-receiving button on said diaphragm, a rotary agitator-element having oppositely extending hubs and peripheral teeth adapted to impinge when rotated upon said impingement-receiving button, means connected with said casing for rotatably journaling the hubs of said agitator, a self-releasing clutch having chamfered clutch-teeth at its lower side, a hub of said agitator having oppositely chamfered clutch-teeth adapted to be operatively engaged by the clutch-teeth of said clutch, said agitator being provided with a tubular slideway, a double-threaded screw-shank mounted to telescope freely into said slideway, inwardly projecting lugs on said

clutch adapted to be engaged by the threads of said screw-shank whereby a rotary movement is imparted to said clutch by an inward movement of said screw-shank, and 5 spring-means for returning said screw-shank to normal initial position.

5. An alarm horn comprising a casing, a diaphragm secured over the open end of said casing, an impingement-receiving button on said diaphragm, a rotary agitator-element having oppositely extending hubs and peripheral teeth adapted to impinge when rotated upon said impingement-receiving button, means connected with said 10 casing for rotatably journaling the hubs of said agitator, a self-releasing clutch having chamfered clutch-teeth at its lower side, a hub of said agitator having oppositely 15 chamfered clutch-teeth adapted to be operatively engaged by the clutch-teeth of said clutch, said agitator being provided with a

20 Copies of this patent may be obtained for five cents each, by addressing the "Commissioner of Patents, Washington, D. C."

tubular slideway, a double-threaded screw-shank mounted to telescope freely into said slideway, inwardly projecting lugs on said clutch adapted to be engaged by the threads 25 of said screw-shank whereby a rotary movement is imparted to said clutch by an inward movement of said screw-shank, said screw-shank having a tubular receiving socket in its lower end, a compression spring arranged in said socket and extending down through said slideway of said agitator, and a keeper-rod extending through the lower portion of said spring.

In testimony that I claim the invention 35 set forth above I have hereunto set my hand this 27th day of May, 1915.

JOHN T. ENGLISH.
